HINGE

John Ludwig, Detroit, Mich.

Application August 19, 1936, Serial No. 96,839

7 Claims. (Cl. 16—164)

My invention relates to a new and useful improvement in a hinge adapted for attachment to a stationary body so as to mount a swingable closure thereon. The present invention forms a development and modification of my invention on a hinge set forth in an application filed by me February 10, 1936, Serial Number 63,148. The present invention has as its object the provision of a hinge so constructed and arranged that a twist of the hinge may be possible so as to properly align the door with the jamb. When the device is used with a vehicle on account of the nature of the vehicle body in which considerable allowance is permitted, it is sometimes necessary to twist the hinges either up or down, or in or out, in order to properly align the door with the jamb so as to compensate for the difference in tolerance permitted on a door and on a vehicle body.

Another object of the invention is the provision of a hinge which will reduce the assembly cost inasmuch as it will permit a quick aligning of the door with the door jamb.

Another object of the invention is the provision of a hinge so constructed and arranged that while having a supporting part of sufficient weight to carry the door it will be sufficiently reduced in strength to permit its distortion.

Another object of the invention is the provision of a hinge of this class having a stop formed thereon so as to render it possible to eliminate the usual stop strap.

Another object of the invention is the provision of a hinge having a pair of cooperating links so constructed as to regulate and control and provide the necessary curve of the swinging of the door.

Other objects will appear hereinafter.

The invention consists in the combination and arrangement of the parts hereinafter described and claimed.

The invention will be best understood by reference to the accompanying drawings which form a part of this specification and in which:

Fig. 1 is the top plan view of the invention showing it applied with parts broken away and parts shown in section.

Fig. 2 is a sectional view taken on line 2—2 of Fig. 1.

Fig. 3 is a sectional view taken on line 3—3 of Fig. 1 with parts broken away.

Fig. 4 is a sectional view taken on line 4—4 of the Fig. 1 with parts broken away.

Fig. 5 is a top plan view of the invention with a part of the supporting frame removed.

Fig. 6 is a view similar to Fig. 1 showing the hinge in partially open position, and

Fig. 7 is a view similar to Fig. 6 showing the hinge in fully open position.

In the drawings I have indicated the invention used with a stationary body 9 associated with which is the swingable door or closure 10. In the body 9, there is formed a recess 11 in which is positioned a U-shaped supporting member 12 having the legs 13 and 14 angularly turned and provided with the flanges 16 and 15 respectively, which are suitably secured to the body 9.

The hinge comprises a section having a substantially U-shaped portion and one leg 18 thereof is seated in a recess 17 formed in the door 10 and secured thereto. The other leg 19 is inclined to the bight 20 and provided with a knuckle 21. This leg 19 is in the form of a plate and an angular extension 22 is formed thereon and provided with a knuckle 23.

Another section of the hinge comprises the sleeve 24 projecting outwardly from the bottom of which is an arm 25, carrying a knuckle at its end. A similar arm 26 projects outwardly from the sleeve 24 at the top thereof and is also provided with a knuckle. The arms 25 and 26 embrace the angularly turned portion or extension 22 and a pintle 28 is extended through the knuckles on the arms 25 and 26 and through the knuckle 23 to pivotally connect these parts together.

Projected through the sleeve 24 and through the parts 13 and 14 is a pintle 27 whereby this section of the hinge is hingedly connected to the supporting body. A sleeve 29 is pivotally connected to the members 13 and 14 by the pintle 30 which projects through members 13 and 14 and through the sleeve 29 and is provided at its upper and lower edges with arms 32 and 31 respectively, the terminal knuckles of the arms embracing the knuckle 21, and a pintle 33 is projected through the knuckles on the arms 31 and 32 and through the knuckle 21. It should be noted that the arms 31 and 32 are of less length than the arms 25 and 26 and this is an important feature in the invention as the difference in the lengths of these arms determines the swing of the door.

As shown in Fig. 2, the leg 18 is of greater width than the bight 20 or the leg 19 so that wings 36 project outwardly from opposite edges 39 of the leg 18. Thus the bight 20 is formed sufficiently narrow to permit the twisting and distorting of the legs 18 and 19 necessary to effect a proper alignment of the door after it is mounted. This distortion may compensate for the dif-

ference in the alignment of the door either inwardly or outwardly or upwardly or downwardly. The presence of wings affords sufficient width to attach the leg 18 to the door, but if desired, these wings may be eliminated and the part 18 formed of the same width as the parts 19 and 20.

As the door begins its initial swing to open position, the supporting body, embodying the parts 18, 19, 20 will move bodily outwardly from the bight 12 of the supporting member for a slight distance and in this outward movement the sleeves 24 and 29 will swing on their pivots. As the door moves into a position where the pintle 28 is in substantial alignment with the pintles 30 and 27, the door will swing on the pintle 33, the sleeve 29 remaining stationary and the sleeve 24 swinging on its pivot. This movement continues until the leg 19 swings past center, after which the sleeve 29 swings its arms inwardly toward the portion 12 of the supporting body and the sleeve 24 will swing outwardly in the opposite direction and at fully closed position the stop shoulder 34 will engage the sleeve 29 and effectively prevent any further swinging. By forming the parts 25 and 26 and the parts 31 and 32 of these relative lengths, it is possible to mount a vehicle body door on a hinge of this kind, so that the door will swing to fully open position and clear the curvature of the body. Difficulty is encountered in this regard unless these parts are of different lengths. The arms 25 and 26 may be termed links connecting the sleeve 24 to the pintle 28 and the arms 31 and 32 may be considered links connecting the sleeve 29 to the pintle 33.

Another advantageous feature of a hinge constructed in this manner is a freedom from a tendency of the door to sag at its outer end.

While I have illustrated and described the preferred form of construction I do not wish to limit myself to the precise details of structure shown but desire to avail myself of such variations and modifications as come within the scope of the appended claims.

Having thus described my invention, what I claim as new and desire to secure by Letters Patent, is:

1. A hinge comprising a substantially U-shaped portion having one of the legs extending diagonally to the bight; an angularly turned portion on said leg, there being a passage formed through said leg at the juncture of said angularly turned portion to provide a knuckle; a supporting body; a pair of links swingably mounted at one of their ends on said supporting body, one of said links being longer than the other, there being a knuckle formed in the end of said angularly turned portion; a pintle projecting through the knuckle at the end of said angularly turned portion and through the free end of the longer of said links; and a pintle projecting through the knuckle formed at the said juncture and through the free end of the shorter of said links.

2. A hinge comprising a substantially U-shaped portion having one of the legs extending diagonally to the bight; an angularly turned portion on said leg, there being a passage formed through said leg at the juncture of said angularly turned portion to provide a knuckle; a supporting body; a pair of links swingably mounted at one of their ends on said supporting body, one of said links being longer than the other, there being a knuckle formed in the end of said angularly turned portion; a pintle projecting through the knuckle at the end of said angularly turned portion and

through the free end of the longer of said links; a pintle projecting through the knuckle formed at the said juncture and through the free end of the shorter of said links; and a shoulder on the end of said leg engageable with the sleeve bearing the shorter of said links for limiting the swinging movement thereof.

3. A hinge comprising a supporting body having oppositely disposed spaced parts, a pair of sleeves positioned between said parts and swingably mounted at opposite sides thereof; a pair of arms carried by each of said sleeves, there being an arm projecting outwardly from each end of each of said sleeves, each of said arms terminating in a knuckle, the arms of one of said sleeves being longer than the other; a substantially U-shaped hinge section having one of its legs extending angularly to the bight and provided with an angularly turned portion, said angularly turned portion having a knuckle formed in its end and said leg having a knuckle formed therein at the juncture of said angularly turned portion and engaging between the shorter of said arms; a pintle projecting through said shorter arms and through the knuckle embraced thereby for swingably connecting the parts together, the knuckle on said angularly turned portion engaging between the longer of said arms; and a pintle projecting through the knuckle on said angularly turned portion and through the knuckles in said longer arms for pivotally connecting the parts together.

4. A hinge comprising a supporting body having oppositely disposed spaced parts; a pair of sleeves positioned between said parts and swingably mounted at opposite sides thereof; a pair of arms carried by each of said sleeves, there being an arm projecting outwardly from each end of each of said sleeves, each of said arms terminating in a knuckle, the arms of one of said sleeves being longer than the other; a substantially U-shaped hinge section having one of its legs extending angularly to the bight and provided with an angularly turned portion, said angularly turned portion having a knuckle formed in its end and said leg having a knuckle formed therein at the juncture of said angularly turned portion and engaging between the shorter of said arms; a pintle projecting through said shorter arms and through the knuckle embraced thereby for swingably connecting the parts together, the knuckle on said angularly turned portion engaging between the longer of said arms; a pintle projecting through the knuckle on said angularly turned portion and through the knuckles in said longer arms for pivotally connecting the parts together; and a stop shoulder on said angularly turned leg for engaging against said sleeve upon relative swinging of said sleeve and said leg to a predetermined position.

5. A hinge of the class described comprising a supporting body having a pair of spaced parts; a pair of sleeves, each swingably mounted between said parts at opposite sides thereof; a pair of arms projected outwardly from each sleeve, one arm projecting outwardly at each end of each sleeve, the arms on one of said sleeves being longer than on the other; a hinge section comprising a substantially U-shaped structure; an angularly turned portion on the ends of one of the legs of said structure and having a knuckle formed in the end thereof, there being a knuckle formed in said leg at the juncture thereof with said angularly turned portion, said leg and said angularly turned portion being of a width for snugly en-

gaging between said arms; a pintle projected through the ends of the shorter of said arms and through the knuckle at said juncture, and a pintle projected through the knuckle at the end of said angularly turned portion and through the longer of said arms and pivotally connecting these parts together.

6. A hinge of the class described comprising a supporting body having a pair of spaced parts, 10 a pair of sleeves each swingably mounted between said parts at opposite ends thereof; a pair of arms projected outwardly on each sleeve, one arm projecting outwardly at each end of each sleeve, the arms on one of said sleeves being 15 longer than on the other; a hinge section comprising a substantially U-shaped structure; an angularly turned portion on the ends of one of the legs of said structure and having a knuckle formed in the end thereof, there being a knuckle 20 formed in said leg on the juncture thereof with said angularly turned portion, said leg and said angularly turned portion being of a width for snugly engaging between said arms; a pintle projected through the ends of the shorter of said

arms and through said knuckle at said juncture; a pintle projected through the knuckle at one end of said angularly turned portion and through the longer of said arms, and pivotally connecting these parts together; and a stop shoulder on 5 said leg engageable with one of said sleeves for limiting the movement of said U-shaped structure relatively to said sleeve.

7. A hinge comprising a substantially U-shaped portion; an angularly turned portion on one of the legs thereof, there being a passage formed through said leg at the juncture of said angularly turned portion to provide a knuckle; a supporting body; a pair of links swingably mounted at one of their ends on said supporting body, one 15 of said links being longer than the other, there being a knuckle formed in the end of said angularly turned portion; a pintle projecting through the knuckle at the end of said angularly turned portion and through the free end of the longer 20 of said links; and a pintle projecting through the knuckle formed at the said juncture and through the free end of the shorter of said links.

JOHN LUDWIG.
